UNITED STATES PATENT OFFICE.

JOHN THOMPSON, OF LITTLE FALLS, NEW JERSEY, ASSIGNOR OF ONE-HALF TO
HAROLD S. SINDLE, OF LITTLE FALLS, NEW JERSEY.

MEANS FOR FEEDING WATER TO BOILERS.

996,812.

Specification of Letters Patent. Patented July 4, 1911.

Application filed December 5, 1910. Serial No. 595,580.

To all whom it may concern:

Be it known that I, JOHN THOMPSON, a citizen of the United States, residing in Little Falls, Passaic county, and State of New Jersey, have invented certain new and useful Improvements in Means for Feeding Water to Boilers; and I do hereby declare the following to be a full, clear, and exact description of the invention, such as will enable others skilled in the art to which it appertains to make and use the same, reference being had to the accompanying drawing, and to letters of reference marked thereon, which form a part of this specification.

This invention relates to means for feeding water to boilers, and particularly to such means as applied to boilers for locomotives and the like where the feeding must be accomplished under varying conditions due to changes in the position of the boiler, alterations in temperature of the atmosphere, etc.

In accordance with my invention, the fire-box of the boiler is provided above the grate with a hollow water conducting means which extends from the front along one side thereof, across the back, and then forward along the other side thereof, the said means preferably consisting of a plate riveted to the shell of the fire-box on the inside thereof in such manner as to form a space between said plate and the shell. The water for feeding the boiler is forced by an injector into the said conducting means at one side thereof near the front of the fire-box and is discharged near the front of the fire-box into the boiler at the other side of said means.

It is well-known that an injector works with the maximum efficiency when it draws its supply from cold water and discharges into hot water, and this is accomplished in and by my invention while at the same time the water, thoroughly heated by its being caused to circulate in close proximity to the fire, enters the boiler at a temperature equaling or approximating that already in the boiler.

In the accompanying drawing, wherein my invention is fully illustrated, Figure 1 is a view partly in side elevation and partly in section showing the rear portion of a boiler and my improved means for feeding the

water thereto; Fig. 2 is a sectional view on the line *x*—*x* of Fig. 1; and Fig. 3 is a similar view on the line *y*—*y* of Fig. 1.

The shell *a* of the boiler is provided at the back with the usual depending portion *b* which forms with the shell *c* of the inclosed fire-box *e* the water-leg *d*.

e is the fire-door and *f* the grate.

g is an injector to which cold water is supplied through the pipe *h* and which, operating by the pressure of the steam in the boiler introduced into the injector through the pipe *i* connecting the injector with the boiler, discharges into a downwardly depending pipe *j*.

Immediately over the grate and preferably below the fire-door *e* is arranged the aforesaid hollow conducting means *k*. In the preferred construction, the said means is formed by an elongated plate *l* which is bulged or channeled lengthwise thereof and riveted along both its long edges to the shell *c*, the said plate extending from the front of the fire-box along one side of the latter to the rear, across the back of the fire-box, and then forward to the front thereof. The riveting may be employed to secure the ends of the plate to the front wall of the fire-box, as shown in Fig. 2, so that the conducting means thus produced is closed at all points except as now to be indicated.

At a point corresponding to the front part of the fire-box and at one side thereof a sleeve *m* is screwed into the walls of the depending portion of the boiler shell and the fire-box. Into this sleeve is screwed a connection *n* to which the lower end of pipe *j* is attached. At the other side of the fire box, and opposite the nipple *n*, a hole *o* is formed, affording communication between the space of the conducting means *k* and the adjoining water-leg of the boiler.

Upon the engineer setting the injector to work it draws cold water from the pipe *h* and forces the water into the conductor *k* out of the same through the opening *o* and into the boiler. The water fed to the boiler is therefore heated to a degree equaling or approximately equaling that already in the boiler, and, owing to the size and form of the conducting means *k* and its close proximity to the fire, this condition must always

exist at times when fresh water is fed to the boiler, so that the danger of explosions or of straining any of the parts or joints of the boiler, due to admitting water at a temperature sufficiently lower than that already in the boiler to produce undue contraction is eliminated.

While my improvements are of peculiar value in connection with locomotive boilers, 10 it will be understood that they are useful in connection with stationary boilers.

Having thus fully described my invention, what I claim as new and desire to secure by Letters Patent is:

- 15 1. In combination, with the fire-box and the boiler, the latter extending along the sides and the back of the fire-box, a water-conducting means comprising an elongated sheet secured along both its longitudinal edges against the front and side walls of the fire-box, being spaced from said walls between said edges and having an inlet near one end thereof and an outlet near the other end thereof, said longitudinal edges of said 20 sheet being substantially straight and parallel with each other substantially from end to end thereof, and the ends of said conducting means being closed by the back wall of the fire-box, substantially as described.
- 20 2. In combination, with the fire-box and the boiler, the latter extending along the sides and the back of the fire-box, a water-conducting means comprising an elongated sheet secured along both its longitudinal edges against the front and side walls of the fire-box, being spaced from said walls between said edges and having an inlet near one end thereof and an outlet near the other end thereof, said longitudinal edges of said 25 sheet being substantially straight and parallel with each other substantially from end to end thereof, substantially as described.

allel with each other substantially from end to end thereof, substantially as described.

2. In combination, with the fire-box and the boiler, the latter extending along the sides and the back of the fire-box, a water-conducting means comprising an elongated sheet secured along both its longitudinal edges against the front and side walls of the fire-box, being spaced from said walls between said edges and having an inlet near 30 one end thereof and an outlet near the other end thereof, said longitudinal edges of said sheet being substantially straight and parallel with each other substantially from end to end thereof, and the ends of said conducting means being closed by the back wall of the fire-box, substantially as described.

In testimony, that I claim the foregoing, I have hereunto set my hand this 3d day of December, 1910.

JOHN THOMPSON.
